ADJUSTABLE RESISTOR OF THE TUBULAR TYPE

Donald F. Hastings, Fair Lawn, and Robert H. Winkler, Maplewood, N. J., assignors to Hardwick-Hindle, Inc., Newark, N. J.

Application November 7, 1945, Serial No. 627,138

8 Claims. (Cl. 201—56)

1

This invention relates to a resistor construction in which the resistor is of the type having the resistance wire wound on a ceramic spool and held in place thereon by any suitable means such as vitreous enamel with a portion of the wire exposed longitudinally of the spool to make a contact track for a contacting device. While we are aware of the fact that many types of resistors of the general type just mentioned have been made, it has been our experience that much trouble has been encountered in making and maintaining a good contact with the exposed wire track. This is especially true where the resistance wire is of a small size in a high resistance unit. Many types of contact devices have been used in the past, but they are all open to the objection that they soon wear off the wire forming the track surface and thus render the device inoperative, this is particularly so if the contact device has to be shifted frequently on the resistor unit. It is therefore the principal object of our invention to provide a resistor construction in which a rolling instead of a scraping contact can be assured throughout the movement of the contact device on the contact track. In securing this object we obtain better contact and longer life of the resistor. Our improved type of construction will be readily understood by reference to the annexed drawing, wherein:

Figure 1 is a plan view of a portion of a resistor with the contact device positioned thereon.

Figure 2 is a sectional view on the line 2—2 of Figure 1.

Figure 3 is a part-sectional and part-elevational view of the right hand portion of the device shown in Figure 2, showing a modified construction.

Figure 4 is a view similar to Figure 3 of a further modified construction.

Figure 5 is a view similar to Figures 3 and 4 but shows a still further modified construction.

In the various views wherein like numbers refer to corresponding parts, 1 is a tubular member of suitable ceramic material wound in the usual manner by a resistance wire 2 which is held to the spool 1 by a vitreous enamel 3. A contact track 4 being left for a contact device to move thereover.

In our improved construction the contact device comprises a band 5 which encompasses or encircles the resistor unit 1. The band terminates in ends 6 and 7. As shown in Figure 2 the end 6 has a portion 8 extruded to provide sufficient threads for a screw 9 which is adapted to pass through the end 7 so as to draw the ends

2

6 and 7 together into clamping or holding engagement with the resistor 1. The band 5 has a pair of outwardly extending spaced lugs 10 and 11 which are preferably formed outwardly from the material of the band 5. The lugs 10 and 11 are located on the band in the same arcuate relationship and each is provided with a perforation 12 which preferably extends downwardly from its lug into the circular part of the band 5 thereby insuring that the parts or pins 13 which project from opposite ends of the roller 14 will be located so that the roller 14 will always contact with the track 4 when the band 5 is slipped along the resistor.

15 Contact may be made with the band through the medium of the end 7 which has a hole 15 therein which may receive a terminal to which a connecting wire is attached.

In the construction as shown in Figure 3, screw

20 9 is replaced by an eyelet 16 and a spring member 17. The amount of tension which the spring exerts depends on the amount which the ends of the eyelet are spun over to hold it in operative position. In Figure 4 the construction is such that the extruded portion 8 need not be used as the screw 9 is supplied with a nut 18 and washer 19 to hold a spring 17 in position. With this construction the amount of tension given the spring 17 can be readily varied. In Figure 5 the construction is very similar to Figure 4 but in place of the spring 17 a spring washer 20 is utilized with a wing nut 21 to adjust the tension of the band 5. However, in either case the construction is such that the band 5 can be readily moved 35 from one position to another and then readily fastened in set position.

Heretofore it has been stated that the wire may be held to the spool by a vitreous enamel but while this way may be considered by some people as the preferred way, it is not the only way and where vitreous enamel is used it sometimes leaves a lump or projection of varying size on the outer surface of the unit and we have found that by the use of spring 17 or 20 or equivalent the band 40 5 may be more readily passed over the lump. It may also be noted that where the resistor spool is wound with fine wire ordinary dragging contact many times will catch into a turn of the wire and rip it loose whereas with our roller contact 45 this difficulty is obviated.

It may be mentioned in passing that the band 5 is made of any suitable material such as 1/2-hard brass, cadmium plated, while the roller may be also made of 1/2-hard brass with a substantial 55 plating of silver. We have found this choice of

materials and arrangement of parts as described to give excellent satisfaction.

Having thus described our invention, what we claim is:

1. A resistor construction including, in combination with a tubular type resistor having a contact track along the length thereof, a band encircling the resistor with means for holding the band in an operative position on the resistor, said band having a pair of spaced outwardly extending lugs, the lugs having perforations therein and a roller mounted between the lugs by parts positioned in said perforations so the roller will engage and roll on said contact track.

2. A resistor construction including, in combination with a tubular type resistor having a contact track along the length thereof, a band encircling the resistor with means for holding the band in an operative position on the resistor, said band having a pair of spaced outwardly extending lugs, the lugs having perforations therein, the perforations extending from the lugs into the circular position of the band and a roller for contacting with and rolling on the track mounted between the lugs by pin-type extensions positioned in said perforations.

3. A resistor construction including, in combination with a tubular type resistor having a contact track along the length thereof, a band encircling the resistor with means for holding the band in an operative position on the resistor, said band having a pair of spaced outwardly extending lugs, thrown outwardly in arcuate alignment from the material of the band, the lugs having perforations therein and a roller having parts positioned in the perforations which are positioned so as to assist in holding the roller in good contact engagement with the contact track.

4. A resistor construction as set forth in claim 1 further defined in that the holding means includes a resilient element.

5. A resistor construction as set forth in claim 1 further defined in that the holding means in-

cludes a resilient element with means for varying the effect of the resilient element.

6. In a resistor construction in which the resistor wire is wound on a ceramic spool and held thereto by a suitable holding means with a longitudinal portion of the wire exposed to make a contact track along the turns of wire, means for making and always assuring a rolling contact with the track, said means comprising a suitable metal band encompassing the spool with means for adjusting the tension of the band around the spool, spaced lugs projecting outwardly on the band and a roller carried by the lugs in a position to contact with and roll on the track when the band is shifted longitudinally of the resistor.

7. A resistor construction as set forth in claim 6 further defined in that the lugs have elongated openings therein extending downwardly into the arcuate surface of the band while the roller has axially located pins extending from each end into their cooperative openings.

8. A resistor construction in which the resistor has a resistance wire winding with a contact track, means for making contact with turns of the wire without a tendency to pull on the wire and thereby cause it to be displaced or broken, said means comprising a band of suitable current conducting material encompassing the spool and a cylindrically shaped roller carried by the band transversely of the axis of the spool in contact with the track and to roll over the turns as the band is shifted longitudinally of the spool.
